STRENGTH TESTING MACHINE

Application filed June 27, 1930. Serial No. 464,143.

This invention is concerned particularly with machines which are intended to be used in testing the weight lifting strength of individuals. As such machines are commonly constructed there is no compensation for the weight of the individual and in a competition between two individuals, one of whom weighs materially more than the other, the heavier individual has an advantage over the other to the extent of his superior weight. It is the object of this invention to produce a machine of this character in the operation of which the person whose lifting strength is being tested must lift his own weight, thereby establishing a fair basis of comparison. In accordance with the invention the individual stands on a platform which is supported at one end upon a horizontal axis, while the handles to which the individual applies his strength are connected to a lever or levers which act against the platform to raise the same through a decreasing leverage, so that while each individual, no matter what his weight may be, must first lift his own weight, he must continue to lift his own weight through a decreasing leverage so that the machine, through indicating devices, will indicate the amount of force exerted by the individual above that represented by his own weight.

The invention will be more fully explained hereinafter with reference to the accompanying drawings in which it is illustrated, and in which:

Figure 1 is a view of the improved machine in sectional elevation.

Figure 2 is a view of the same in elevation as seen from the left hand in Figure 1.

Figure 3 is a view in horizontal section on the plane indicated by the broken line 3—3 of Figure 1.

Figure 4 is a detail view in perspective of a portion of an indicating device which may be used.

Figure 5 is a detail view illustrating the changing relation between the platform and the force supplying lever, the platform being shown as somewhat shorter than in Figure 1.

Figure 6 is a further detail view of a portion of the indicating device employed.

The machine comprises a suitable housing *a* which also supports the devices to be referred to. The platform *b* is pivoted at *b*¹ within the frame and carries outside of the housing a platform *b*² on which the individual may stand. The operating levers *c*, suitably spaced so that the individual may stand between them as he stands on the platform and suitably shaped, as at *c*¹, to be grasped by the individual, are pivotally mounted within the housing, as at *c*². They may be braced within the housing by cross bars *c*³. Under the two bars which form the platform lever are pivotally mounted, as at *d*¹, corresponding levers *d*, which are cam-shaped on their upper edges, as at *d*², to coat with the lower edge *b*³ of each of the levers *b* so that, as the levers *d* are raised, the point of contact between the levers *d* and the levers *b* will be shifted toward the pivot line of the levers *b*, as indicated in Figure 5, and the leverage through which the levers *d* act upon the levers *b* will be decreased and the strength required to lift the weight of the individual will be increased. For the purpose of raising the levers *d* the operating levers *c* are connected with the levers *d* by any convenient means such as the chains *e*. For the purpose of counterbalancing the weight of the levers and their connections the levers *c* may be connected by links *f* with counterbalance levers *f*¹ mounted on suitable supports *f*².

Any suitable means may be provided for indicating the force exerted by the individual in raising his own weight through the decreasing leverage with which the levers *d* act upon the supporting levers *b*. In the embodiment of the invention illustrated in the drawings one of the operating levers *c* is shown as connected by a link *g* with a rod *g*¹ which is pivoted at *g*² and is connected with a suitable source of electric current supply, such as a battery indicated at *h*. In operative relation with the rod *g*¹ are a series of electrical contacts *i*, *i*¹ etc. disposed so that contact is made successively and connected respectively with electric lamps *h*, *h*¹ etc., which are in turn connected in multiple, through a connection *l* with the battery *h*. The lamps are placed severally in cells *m*, *m*¹ etc., the fronts

of which are closed by glasses which bear numerals indicating the amount of strength exerted by the individual in lifting his own weight.

5. It will be understood that in operation the individual first lifts his own weight through a leverage which is the same for all and then lifts his own weight with a decreasing leverage which requires the exertion of greater strength and that the extent to which the individual is able to raise his own weight, as shown progressively by the indicating devices, is a fair measure of the strength of the individual.
10. It will be understood that for convenience and to avoid confusion but few indicating lamps have been shown. It will also be understood that other indicating devices may be substituted for the lamps and that various other changes may be made for the convenience of the user or that the manufacturer may suggest without departing from the spirit of the invention as the same is set forth in the accompanying claims.
15. We claim as our invention:
  1. A strength testing apparatus comprising a movable platform on which the operator may stand, an operating handle, operating connections between the handle and the platform whereby the operator must lift his own weight, means whereby the leverage of the connections is decreased as the platform is raised, and indicating means connected to the handle to indicate the extent of movement of the handle.
  2. A strength testing apparatus comprising a platform on which the operator may stand, a lever on which the platform is supported, an operating handle, a lever acting upon the platform lever, means whereby the leverage between the two levers is decreased as the platform is raised, a connection between the handle and the second named lever, and indicating means connected to the handle to indicate the extent of movement of the handle.
  3. A strength testing apparatus comprising a platform on which the operator may stand, a lever on which the platform is supported, a second lever in operative relation with the lever platform and having a cam surface for engagement with the platform lever to cause decreasing leverage between the levers upon the raising of the platform, an operating handle, means connecting said handle to the second lever, and indicating means connected to the handle to indicate the extent of movement of the handle.

This specification signed this 25th day of

60 June, A. D. 1930.
